POP-UP FIGURE TOY OR THE LIKE

John M. Auzin, Whitman, Mass.

Application March 19, 1952, Serial No. 18,971

Term of patent 14 years

(Cl. D34—2)

To all whom it may concern:

Be it known that I, John M. Auzin, a citizen of the United States, residing at Whitman, State of Massachusetts, have invented a new, original, and ornamental Design for a Pop-Up Figure Toy or the like, of which the following is a specification, reference being had to the accompanying drawing, forming a part hereof.

In the drawing,

Fig. 1 is a front elevational view of a pop-up figure toy or the like embodying my new design; Fig. 2 is a side view thereof; and

Fig. 3 is a view similar to Fig. 1, with the upper portion in outwardly extended position.

I claim:

The ornamental design for a pop-up figure toy or the like, as shown.

JOHN M. AUZIN.
